PNEUMATIC FRACTIONATING APPARATUS

This invention relates to the fractionation of a solid, particulate mixture, and particularly to pneumatic apparatus for separating particle fractions from a mixture thereof.

It is known to fractionate solid, particulate mixtures having uniform particle sizes up to about 30 mm by means of a gas stream entering the mixture through a perforated plate on which the mixture is supported, whereby a fraction of lower specific gravity is entrained in the air stream and recovered therefrom in purified form, whereas impurities of higher specific gravity accumulate on the plate and may be withdrawn separately. The known pneumatic fractionating or classifying devices that have been found effective are relatively costly to build and operate, and less elaborate devices achieve only insufficient separation of the fractions.

It is a primary object of this invention to provide a fractionating apparatus for particulate mixtures which is simple and inexpensive to build and operate, yet cleanly separates fractions of different specific gravity in a mixture of approximately uniform particle size or particles otherwise differing in their interaction with a rising stream of gas.

In its more specific aspects, the invention provides apparatus in which a conduit is mounted on a support in an upright position. An obliquely sloping end wall formed with a multiplicity of apertures downwardly bounds the axially terminal bottom portion of the bore in the conduit when the apparatus is in its operative condition. The particulate material to be fractionated is fed to the bottom portion of the conduit, and a stream of fluid is passed through the apertures in the end wall into the bore of the conduit, and thence into a collecting vessel communicating with the axially terminal top portion of the conduit by a suction blower which produces and maintains a pressure differential between the several parts of the apparatus and a source of the fluid, such as ambient, atmospheric air. The fluid stream, when suitably matched to the feeding rate for the mixture, entrains only lighter particles and deposits them in the collecting vessel, whereas a heavier fraction accumulates on the apertured end wall, and may be withdrawn therefrom from time to time.

Other features, additional objects, and many of the attendant advantages of this invention will readily be appreciated as the same becomes better understood by reference to the following detailed description when considered in connection with the appended drawing in which:

FIG. 1 shows fractionating apparatus of the invention in elevation and partly in section; and

FIGS. 2 and 3 show modifications of the apparatus of FIG. 1 in fragmentary corresponding views.

Referring now to the drawing in detail, and initially to FIG. 1, there is seen a feed hopper 1 containing the particulate mixture 2 which it is desired to fractionate. An upright valve plate or flap 3 held in a desired vertical position by a clamping screw 4 controls the size of an opening 22 which admits material from the obliquely sloping bottom wall of the hopper 1 to an end wall 5 of a shaft 6. The wall 5 is a screen or perforated plate whose apertures are preferably small enough not to pass the particles of the mixture 2. The end wall 5 slopes obliquely relative to the vertical axis of the shaft 6 toward the circumferential wall portion which is common to the shaft 6 and the hopper 1 and divides the

hopper from the shaft, the latter being a straight sheet-metal conduit having a bore of square cross section.

The axially terminal, upper portion of the bore in the shaft 6 communicates with a collecting vessel 7 whose upper part is cylindrical and whose bottom wall conically tapers toward a central slide valve 21. A suction system including an exhaust blower, not shown, communicates with the top portion of the vessel 7 through a suction conduit 8.

The shaft 6 and hopper 1 are supported on a sheet metal base 20 laterally closed in three directions so as to provide guidance to an air stream represented by arrows 9 toward the face of the end wall 5 outside the bottom portion of the shaft 6, and to guide the air stream through the apertures in the end wall 5 toward the circumferential portion of the shaft 6 which is formed with the opening 22.

A lower oblique edge 10 on each of two opposite shaft walls guides pins, obscured in the drawing, which project from the lower edge of the end wall 5 at right angles to the plane of the drawing. The top edge of the apertured end wall 5 projects beyond the shaft 6 and carries a handle 14. It is releasably secured to the shaft 6 by a permanent magnet 16. Prongs 15 project from the bottom edge of the end wall 5 through respective openings, not explicitly shown, in the axial wall part 24 of the shaft 6 spacedly below the opening 22 so as to secure the end wall in the illustrated operative position, in which a pocket 11 is formed between the end wall 5 and the upright wall part 24 of the shaft 6 below the opening 22.

A pan 19 positioned in the base 20 catches any fines that may drop through the apertures in the end wall 5. When the end wall 5 is pulled obliquely upright and toward the left, as viewed in the drawing, by means of the handle 14, all material carried on the wall 5 drops into the pan 19 through the gap opening between the lower edge of the end wall 5 and the axial wall part 24.

A short duct 17 arranged on the shaft 6 at about one third of its height on the axial wall opposite the opening 22 is provided with a hinged flap 18 which permits the duct 17 to be sealed or to be opened to any desired flow section for admitting ambient air when the exhaust blower (not shown) draws air from the vessel 7.

The afore-described apparatus operates as follows:

When the non-illustrated blower produces a pressure differential between the two faces of the end wall 5, a stream of air is guided into the bottom portion of the shaft 6 by the base 20 in such a direction as to blow particles on the wall 5 upward and toward the opening 22. The particulate mixture 2 flows from the hopper 1 into the shaft 6 under the force of gravity at a rate determined partly by the size of the opening 22 between the valve plate 3 and the top rim of the wall part 24 set by the clamping screw 4. The rate of particle flow is also affected by the rate at which particles are removed from the end wall 5 toward the collecting vessel 7 and by the resistance of the air stream 9. The valve plate 3 is readily set in such a manner that the portion of the end wall 5 in the shaft 6 near the handle 14 is free from particles of the mixture at all times, and the air is freely discharged in this area from the apertures in the wall 5, while an almost stagnant body of particles accumulates in the pocket 11.

Under such operating conditions, the lighter particles, presumed to be those of the product to be purified, are lifted into the vessel 7 where they settle from

the air stream whose velocity suddenly decreases as it emerges from the relatively narrow shaft 6 into the wide vessel 7. The product particles may be withdrawn through the valve 21 from time to time, or the valve may be replaced by a screw conveyor for continuous product discharge without loss of suction, if so desired. Secondary air admitted through the duct 17 permits a high air velocity to be maintained in the top portion of the shaft 6 for sufficient lifting action without causing excessive turbulence in the fractionation or classification area immediately above the end wall 5, and particularly in the pocket 11 in which a heavy fraction is trapped, and from which it may be released from time to time after closing the opening 22, and shutting down the non-illustrated blower as soon as all product particles have been blown from the end wall 5 into the collecting vessel 7.

The suction system represented in the drawing only by the suction conduit 8 may include a cyclone for removing entrained fine particles from the withdrawn air, and further includes the necessary drive for the blower, electric switch gear, and like conventional elements, not shown.

If it is desired for any reason to interrupt operation of the apparatus and to empty the shaft 6, the handle 14 may be released from the magnet 16 after the valve plate 3 was lowered until it engages the rim of the wall part 24, and the end wall 5 may be pivoted on its prongs 15 and the non-illustrated guide pins to drop the particles from the shaft 6 into the pan 19. The contents of the hopper 1 may thereafter be discharged by raising the valve plate 3.

Practically perfect separation of two particle fractions differing in specific gravity, but approximately equal in size, is achieved by the oblique inclination of the apertured end wall 5 toward the pocket 11. Due to gravity and agitation by the passing air, the heavier particles tend to migrate downward along the end wall 5 while the lighter particles tend to migrate upward. The air velocity is highest through the upper portion of the wall 5 where there is no overlying particulate material, and it is very low in the pocket 11 where the particle layer is thickest. The lighter particles, therefore, migrate toward the area of greatest air velocity and tend to be entrained by the rapid stream of fluid while they are almost free from the heavier fraction. The heavier particles accumulating in the pocket 11 are held there by gravity and are not exposed to an air stream rapid enough to dislodge them. Very little air normally enters the shaft 6 through the opening 22, the particulate material 2 in the hopper 1 providing a practically airtight seal, and such air as may be drawn through the opening 22 passes above the pocket 11.

The purity of the separated fractions of a given mixture depends, under otherwise constant conditions, on the angle of inclination of the end wall 5. The illustrated fractionation apparatus is intended for continuous operation on a uniform product so that the angle of inclination of the end wall 5 is fixed at an optimum value determined previously by trial and error.

The apparatus of FIG. 1 is readily modified for fully automatic operation as is shown in FIG. 2. The operating cycle is controlled by a rotary timing switch 50 connected by conductors 58, 60 to solenoid valves of reversible pneumatic motors 52, 56. The pressure lines supplying compressed air to the cylinders of the motors

52, 56 and associated manual shut-off valves have been omitted from the drawing.

The piston rod of the motor 52 is attached to a valve plate 54', closely similar in structure and function to the afore-described valve plate 3, and shifts the valve plate 54' upward from the illustrated position in which it radially closes the shaft 6 when the valve of the motor 52 is energized.

The shaft 6 is downwardly bounded under normal operating conditions by a flat screen 54 guided obliquely relative to the vertical axis of the shaft 6 by two guide rails 62 of which only one is seen in FIG. 2. As illustrated in FIG. 2, the solenoid valve of the motor 56 is energized, and the piston rod of the motor 56 holds the screen 54 in a position in which it permits accumulated impurities 58 to be discharged by gravity from the bottom of the shaft 6.

When the current in the conductors 60 is shut off by the switch 50, the motor 56 pushes the screen into its normal operating position in which it permits the entry of air into the shaft 6 from below, but substantially prevents discharge of particulate solids. When, thereafter, the conductors 58 receive current from the switch 50, the valve plate 54' is raised and the apparatus of FIG. 2 assumes a condition analogous to that shown in FIG. 1 until the switch 50 restores the positions of the valve plate 54' and of the screen 54 after a period whose length may be set on the switch 50 in a conventional manner.

FIG. 3 shows a modification of the device of FIG. 2 in which impurities may be released from the shaft 6 by pivoting the screen 30 normally serving as an obliquely inclined bottom wall for the shaft. The upper edge of the screen 30, otherwise similar to the screen 54, is attached to the shaft 6 by means of a pivot shaft 32. An arm 42 fixedly attached to the screen 30 is hingedly fastened to the piston rod of a double-acting pneumatic motor 40 controlled by a built-in solenoid valve as described above with reference to the motor 56.

When the solenoid is energized, the motor 40 pivots the screen 30 into the illustrated position. When the solenoid is deenergized, compressed air in the motor 40 swings the screen 30 counterclockwise, as viewed in FIG. 3, against a sealing plate 34 mounted on the shaft 6 by means of releasable fasteners for vertical adjustment as indicated by a double arrow.

The sealing rail determines the angle at which the screen 30 is inclined relative to the vertical axis of the shaft 6, and thus permits the apparatus to be adjusted for the properties of material to be processed.

Other variations and modifications of the illustrated examples of the invention will readily suggest themselves to those skilled in the art, and it will be appreciated that this invention, within the scope and spirit of the appended claims, may be practiced otherwise than as specifically disclosed.

I claim:

- 60 1. Apparatus for fractionating particulate material comprising, in combination:
  - a. a support;
  - b. a conduit mounted on said support in a position which is upright in the operative condition of the apparatus;
  - 65 1. said conduit having an axis and an axial wall circumferentially bounding an axial bore in said conduit,

2. said bore having axially terminal top and bottom portions bounded by respective upper and lower terminal parts of said axial wall,
3. said axial wall being formed with an opening spacedly adjacent said lower terminal part thereof,
- c. an end wall formed with a multiplicity of apertures and inclined relative to said axis,

  1. said end wall downwardly bounding said bottom portion in said operative condition;
  2. the lowermost portion of said end wall and said lower terminal part bounding a pocket extending downward from said opening;
  - d. feeding means for feeding the particulate material to be fractionated to said opening;
  - e. a collecting vessel communicating with said top portion; and
  - f. pressure means for passing a stream of fluid through said apertures into said bore, and through said bore into said collecting vessel.

2. Apparatus as set forth in claim 1, wherein said feeding means including a hopper communicating with said bore through said opening.
3. Apparatus as set forth in claim 2, wherein said hopper extends upward from said opening for gravity flow of said material into said bore, said feeding means further including valve means for controlling the rate of said flow.
4. Apparatus as set forth in claim 3, wherein said valve means include a closure member secured to said conduit for movement between a plurality of positions in which said closure member defines respective different flow sections of said opening.
5. Apparatus as set forth in claim 4, further comprising means for securing said closure member in each of said positions.
6. Apparatus as set forth in claim 1, further comprising

- ing means for securing said end wall in each of a plurality of positions of different angular inclination relative to said axis.
7. Apparatus as set forth in claim 1, further comprising discharging means for discharging from said bottom portion a fraction of said material accumulating in said pocket.
  8. Apparatus as set forth in claim 7, wherein said discharging means include means for withdrawing said lowermost portion of said end wall from said lower terminal part, and for thereby opening a downwardly directed gap between said lowermost portion and said lower terminal part.
  9. Apparatus as set forth in claim 8, further comprising guide means for substantially maintaining the oblique inclination of said end wall relative to said axis during said withdrawing.
  10. Apparatus as set forth in claim 7, further comprising operating means for operating said feeding means and said discharging means in timed sequence.
  11. Apparatus as set forth in claim 10, wherein said operating means include means for alternatively operating said feeding means and said discharging means.
  12. Apparatus as set forth in claim 7, wherein said discharging means include means for pivoting said end wall away from the position in which said end wall bounds said bottom portion.
  13. Apparatus as set forth in claim 1, further comprising guide means for guiding said stream of fluid toward a face of said end wall outside said pocket in a direction toward said opening.
  14. Apparatus as set forth in claim 1, wherein said pressure means include means for withdrawing said fluid from said collecting vessel at a pressure lower than atmospheric pressure, said apertures communicating with the ambient atmosphere.
